UNITED STATES PATENT OFFICE

CLIFFORD E. SCOTT, OF MINNEAPOLIS, MINNESOTA, ASSIGNOR TO MCQUAY RADIATOR CORPORATION, OF MINNEAPOLIS, MINNESOTA, A CORPORATION OF DELAWARE

HEAT UNIT AND CABINET

Application filed January 16, 1928. Serial No. 247,159.

My present invention relates to a heat unit and cabinet and has for its object to improve the same in the several particulars hereinafter noted.

5 To the above end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in front elevation and partly in central vertical section showing 15 the improved heat unit and cabinet;

Fig. 2 is a view in horizontal section taken on the line 2—2 of Fig. 1;

Fig. 3 is a fragmentary end elevation with some parts sectioned on the line 3—3 of Fig. 20 1; and

Fig. 4 is a fragmentary perspective view showing one of the pairs of apertured lugs in the cabinet.

The numeral 5 indicates a sheet metal heat 25 cabinet having an open bottom and a displaceable cover. In the front of the cabinet 5 at the top thereof is a grille 6. This cabinet 5 is rectangular in cross section and provided at its four corners with supporting legs 7 having 30 fixed upstanding screw-threaded stems 8. Said stems 8 extend through apertured lugs 9 rigidly secured to the cabinet 5 and having applied thereto pairs of nuts 10 in opposing relation between which said lugs extend.

35 These nuts 10 rigidly connect the cabinet 5 to the stems 8 and adjustably support the same in true horizontal position with its lower end at substantially the top of the legs 7.

Within the cabinet 5 is a heat unit 11 in the 40 form of a cellular or tubular radiator, the air passages of which extend vertically. Said heat unit 11 has at each end a header 12 into one end of which is tapped a supply pipe 13 of a heating system using a heat exchange medium such as vapor or steam. In the corners of the headers 12 are apertured ears 14 through which the stems 8 extend. Pairs of nuts 15 in opposing relation are applied to the stems 8 below the pairs of nuts 10 and between which the ears 14 project and adjust-

ably support the heat unit 11 in an inclined position in the cabinet 5 to drain any condensation which may take place therein to the supply pipe 13 which is also supported at a grade that will return said condensation to the boiler of the heating system. The heating unit 11 is of such size as to snugly fit within the cabinet 5 and which cabinet acts as a stack for creating a natural draft in the cabinet 5 which passes upward through the air passages in the heat unit 11.

Obviously, cold air is taken into the cabinet 5 through the open bottom thereof and passes upward through the heat unit 11 where the same is heated and drawn upward through the cabinet 5 and out into the room through the grille 6.

By independently and adjustably supporting the cabinet 5 and heat unit 11 from the legs 7, said cabinet may be adjusted into a true horizontal position so that the lower edge thereof is at substantially the top of the legs 7, as previously stated, which gives the cabinet 5 a neat and finished appearance and at the same time this independent adjustment permits the heat unit 11 to be angularly adjusted within the cabinet 5 where the same is out of sight so as to drain any condensation which may take place therein into the supply pipe 13.

In some types of heating systems a return pipe will be tapped into the header 12 opposite from the supply pipe 13.

What I claim is:

1. The combination with a heat cabinet 85 having supporting legs, of a heat unit in the cabinet and having a supply pipe and apertured ears, said legs having screw-threaded stems extending through said ears and provided with nuts adjustably supporting the 90 heat unit in a position in which it will drain into the supply pipe.

2. The combination with a heat cabinet having supporting legs, of a heat unit in the cabinet and having a supply pipe, said legs having stems on which the cabinet is supported, said heat unit being adjustably mounted on the stems in a position in which it will drain into the supply pipe. 95

3. The combination with a heat cabinet 100

- having supporting legs and apertured lugs,
 said legs having screw-threaded stems ex-
 tending through said lugs and having nuts
 adjustably supporting the heat cabinet, of a
 heat unit in the cabinet and having a supply
 5 pipe and apertured ears through which said
 stems extend, said stems having other nuts
 adjustably supporting the heat unit in a po-
 sition in which it will drain into the supply
 pipe.
- 10 4. The combination with a heat cabinet, of
 a heat unit in the cabinet, and supporting legs
 for the heat cabinet and heat unit, said heat
 cabinet and heat unit being mounted on the
 legs for independent adjustments.
- 15 5. The combination with a heat cabinet, of
 a heat unit in the cabinet, and supporting legs
 for the heat cabinet and heat units, said heat
 cabinet being adjustable in respect to said
 legs and heat unit.
- 20 6. The combination with a heat cabinet, of
 a heat unit in the cabinet, and supporting legs
 for the heat cabinet and heat unit, said legs
 having upstanding stems on which the heat
 cabinet and heat unit are independently re-
 25 movably and adjustably mounted.

In testimony whereof I affix my signature.
 CLIFFORD E. SCOTT.
